CLAIM

The ornamental design for a housing of a spectacle elastic hinge, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of a housing of a spectacle elastic hinge showing my new design;

FIG. 2 is a front view thereof, the rear view being a mirror image of the FIG. 2 view;

FIG. 3 is a right side view thereof;

FIG. 4 is a bottom view thereof;

FIG. 5 is a left side view thereof; and,

FIG. 6 is a top view thereof.
